UNITED STATES PATENT OFFICE.

FRANK B. SANBORN, OF CAMBRIDGE, MASSACHUSETTS.

DEVICE FOR USE IN CONNECTION WITH VELOCITY-INDICATORS.

1,099,206.

Specification of Letters Patent.

Patented June 9, 1914.

Application filed December 29, 1910. Serial No. 599,875.

To all whom it may concern:

Be it known that I, FRANK B. SANBORN, a citizen of the United States, and a resident of Cambridge, in the county of Middlesex and State of Massachusetts, have invented certain new and useful Improvements in Devices for Use in Connection with Velocity-Indicators.

My invention relates to a device for receiving and transmitting dynamic fluid pressure that is due to the velocity of a fluid relative to a stationary or moving object.

One important function of the invention is to provide a device that will receive and transmit accurately the pressure of water that is caused by a moving boat, thus to enable the speed of the boat to be indicated.

Another object of the invention is to enable the velocity of water that is flowing relatively to a boat at anchor to be similarly indicated; it will likewise indicate the velocity of water that is flowing relatively to any stationary structure whereto the device may be attached.

Another object of the invention is to provide a device that will receive and transmit accurately the pressure of a fluid due to its relative velocity, and at the same time one that will not easily become inoperative on account of obstructions due to grass, seaweed, or floating debris; and furthermore to provide a device such that, perchance it becomes obstructed, it can be freed of such obstructions without disconnecting pipes or attachments, or removing any of its parts.

Another object of the invention is to provide a device that can be readily attached to the bottom of a boat even while the boat is floating in water. And finally it is important that the whole device shall cause no material obstruction to the free flow of water past or relative to, the device.

Other objects of the invention will be apparent from the following description and reference to the accompanying drawings which form a part of this specification.

Figure 1 is a longitudinal vertical section, partly in elevation, showing one embodiment of my present invention. Fig. 2 is a front end elevation of the device. Fig. 3 is a modified form of the valve and seat of member A which is shown in Figs. 1 and 2. Fig. 4 is a plan view when a portion has

been removed leaving the body portion and its associated curved tube and connecting pipe. Fig. 5 is a side elevation of the portion shown in Fig. 4.

The body portion or supporting and protecting member 10 of the device is shown in Figs. 1, 2, 4 and 5. Associated with this body portion is the shoulder 11, the tube 12, the pipe 13, the clearing member or ejector A and the outlet T or member 14. The body portion serves as a support for the curved tube 12 and by extending beyond the tube as shown in Fig. 1 the body portion gives protection to the tube against the impact of water, floating substances, mud, or shoals. The bent tube 12 has the approximate form shown in Figs. 1 and 5. When in operation water or fluid enters this tube, fills it as well as the pipe 13, the outlet T or member 14, and the pipe or tube connects to some form of gage or indicating means which can be of any particular form or variety and is therefore not shown herein.

Through the tube 12 and the pipe 13 passes a clearing member or ejector A that is composed of the parts 15 and 16. This member serves specifically for freeing the tube 12 of possible obstructions. It is ordinarily in the position shown in Fig. 1 and its adjustable handle 21 is then in the vertical position shown in Figs. 1 and 2, but when this member is needed for the purpose of removing possible obstructions in the tube 12, then the handle is brought approximately into a horizontal position as shown in Fig. 1 where it can be easily grasped in the hand; pressure applied to the handle will force the member along the tube so that the end of the clearing member will extend out through the tube as shown in Fig. 1, thus removing any obstructions that may have existed. Furthermore the clearing member A is provided with a conical shoulder 17 which engages with the seat 18 when the member is forced down and thus the inflow of water or other fluid can be shut off.

In order to prevent leakage of water or other fluid from the chamber through which the member A operates and along said member, the packing nut 19 is used. Also to prevent the clearing member A from being accidentally drawn through the packing nut 19 the shoulder 20 is provided.

Having thus described the essential parts of my invention and its method of operation as applicable to boats, air crafts or stationary objects, where occurs a relative velocity of water or other fluid, I will now explain a method of attaching the device to a boat that is floating in water. First, the clearing member A with its handle 21 and the outlet T or member 14 are separated from the other parts by unscrewing the threaded joint at the end of the pipe 13; the nut 22 and the washer 23 are also removed. The body portion 10 with its associated parts 11, 12 and 13 as shown in Fig. 5 is then ready for attachment to the boat. A hole about one-half inch in diameter is bored through the shell 24 of the boat and at a point preferably near amidships, a few inches away from the keel. The inflow of water is partly stopped by holding a finger over the hole or by inserting a temporary plug; then a strong piece of twine, as a cod-fish line, or a small chain is lowered through the hole (which may still be kept partly closed by a finger, or a plug) until it can be reached by a boat hook or a grapple, from the outside of the boat. The loose end of the twine, or chain, is then drawn above the water surface and the portion of the device shown in Fig. 5 is attached thereto. The attachment is made by fastening an end of the twine, or chain, inside the pipe 13 or by passing the twine or chain through the pipe 13 and the tube 12 and then merely tying a knot or inserting in the knot a nail or small cross-bar of metal or stone so as to aid later in removing from the tube the cut or broken end of the twine or chain. As soon as the twine, or chain, has been attached the parts are lowered into the water and the other end of the twine or chain is pulled into the boat until the pipe 13 is drawn up through the hole in the shell of the boat, thus enabling the metal washer 23 and the nut 22 to be put on. Before tightening the nut 22 the guide marks 27-27 on the end of the pipe 13 are brought into a direction that is parallel with the keel of the boat, and also the most distinctive of the above marks, as well as the distinctive mark 26, on the side of the pipe 13, are placed forward, toward the bow. When the device is in this position the end of the curved tube 12 will face toward the bow and will receive the pressure of water that is moving relatively to the boat. In the case of boats with wooden shells, such as most motor boats have, when nut 22 is being tightened, it will facilitate the adjustment to pull the pipe 13 and at the same time to rock the parts slightly forward and backward so that the points 25 25 25 will be quickly indented into the wood and the device brought to a rigid position. Also when the nut 22 is firmly tightened the shoulder 11, which is slightly cup-shaped

and has a circular edge, will be indented into the wood and by this means will form a water-tight joint.

Either before, or after the nut 22 is in final position, the twine, or chain, may be cut or broken and the portion of it that is within the pipe and tube may be allowed to fall downward into the water; the remaining parts of the device can then be connected and any inflow of water stopped. The portion 16 of the clearing member A is made of material that is springy and will easily pass through the tube 12 which is made of smooth tubing. The outlet T or member 14 has an inside thread which fits the outside thread of the pipe 13 and when this T or member has been turned into place, the clearing member can be put into its normal position by causing the handle 21 to drop into the position shown in Figs. 1 and 2.

The total time for making the above described attachment which may include the time for boring a hole through the boat, attaching the twine, or chain, pulling the parts into place, tightening the nut on the inlet pipe, inserting the clearing member and screwing on the outlet T will rarely be more than fifteen minutes and during the process only a few gallons of water need to leak into the boat.

I have endeavored to give in the foregoing paragraphs a complete and exact description of the method of operation of my invention and the method of attaching the device to boats, but it will be understood that changes and modifications can be made in the device herein shown without departing from the spirit of the invention.

What I claim as new and desire to secure by Letters Patent is:—

1. A testing apparatus for use in connection with devices for velocity indicators comprising a curved tube and a body portion with a reduced edge that lies in a plane substantially parallel with a plane through the axis of the bent tube and said body portion extending beyond the tube in opposite directions.

2. A testing apparatus for use in connection with velocity indicators comprising a body portion provided with a reduced edge that serves as a cut-water or divider and with a projecting shoulder and associated with said body portion a curved tube that passes through the shoulder which forms a support when drawn against a surface of wood or yieldable material.

3. A testing apparatus comprising a cut-water, and an inlet tube, provided with a cup-shaped shoulder with a projecting edge that forms a water-tight joint when indented in wood or yieldable material.

4. A velocity indicator comprising a plate and an inlet tube, the tube having an open end protected against the entrance of solid

material by an edge of the plate that extends beyond the tube.

5. A velocity indicator comprising an inlet tube and a deflector having an edge situated in advance of the inlet tube and being inclined past the tube opening.

6. A velocity indicator comprising an inlet tube, arranged to open in the direction of progress, and a plate situated in advance 10 of the inlet tube and having its forward edge inclined downwardly toward the tube opening.

7. A velocity indicator for use in connection with boats comprising an inlet tube 15 adapted to extend inside and outside the hull of the boat, an ejector in the tube movable through the outer end thereof, and means for actuating the ejector situated at the inner end of the tube.

20 8. A velocity indicator comprising a cut-water, an inlet tube associated therewith, an ejector therein, a handle for actuating the ejector and operable from without the tube.

9. A velocity indicator comprising an inlet tube, an ejector operable from without 25 the tube, and indicating means for showing the position of the ejector and for retaining the ejector in position.

10. A velocity indicator comprising an inlet tube and a clearing device that has means 30 for closing the tube, said device operating to clear the tube upon the closure thereof.

11. A testing apparatus for use in connection with velocity indicators comprising 35 a cut-water, an inlet tube associated therewith, and a combined ejector and shut-off valve coöperating with the inlet tube.

12. In a velocity indicator for use in connection with boats, the combination with a

plate, of means for fixing the plate to a 40 boat substantially at right angles to the hull, and an inlet tube carried by the plate.

13. In a velocity indicator for use in connection with boats, the combination with a plate, of means for fixing the plate to a boat 45 in a definite position, and an inlet tube carried by the plate extending first outwardly from the hull and then forwardly to an opening within the area of said plate.

14. In a velocity indicator, a plate having 50 means for securing it with an edge engaging the hull of a boat, and an inlet tube mounted upon one side of the plate.

15. In a velocity indicator, a triangular plate, means along one edge of the plate for 55 securing it to the hull of a boat, and an inlet tube extending from said edge toward an apex of the plate.

16. In a velocity indicator, the combination with a body portion, having an annular 60 shoulder, of an inlet tube extending from the shoulder along the body portion.

17. In a velocity indicator, the combination with a body portion, of an annular shoulder, and an inlet tube extending from 65 the shoulder along the body portion, the body portion and shoulder having means for engaging the hull of a boat.

18. In a velocity indicator, the combination with a body portion, of an annular 70 shoulder, an inlet tube extending from the shoulder along the body portion, and a pipe engaging the shoulder at the opposite side from the inlet tube.
